UNITED STATES PATENT OFFICE.

WALTER E. SCHIMMEL, OF WATERTOWN, WISCONSIN.

HUMIDOR.

1,145,218.

Specification of Letters Patent. Patented July 6, 1915.

Application filed September 6, 1912. Serial No. 718,789.

To all whom it may concern:

Be it known that I, WALTER E. SCHIMMEL, a citizen of the United States, and resident of Watertown, in the county of Dodge and State of Wisconsin, have invented new and useful Improvements in Humidors, of which the following is a description, reference being had to the accompanying drawings, which are a part of this specification.

10 This invention relates to improvements in humidors for charging the atmosphere with moisture, and is more particularly adapted for use in maintaining a constant degree of moisture within cigar cases and 15 the like.

It is one of the objects of this invention to provide a humidor which will evaporate a greater amount of moisture than humidors of ordinary construction, and which is 20 adapted to charge the atmosphere with moisture to a greater or less extent, as desired.

A further object of the invention is to provide a humidor in which electrical means 25 is utilized to expedite and control the evaporation of the water for humidifying the atmosphere.

A further object of the invention is to provide a humidor which is of very simple 30 construction, is easily operated, and which is inexpensive to manufacture.

With the above and other objects in view the invention consists of the improved humidor and its parts and combinations, as set 35 forth in the claims, and all equivalents thereof.

In the accompanying drawing in which the same reference characters indicate the same parts in all of the views: Figure 1 is 40 a central vertical sectional view of the improved humidor; and Fig. 2 is a transverse sectional view thereof.

Referring to the drawing the numeral 5 indicates the receptacle of the improved 45 humidor, 6 the legs thereof and 7 the cover which is hinged to the upper edge of the receptacle. The receptacle, including the cover, is of oval formation in cross section with the major axis of the oval extending 50 in a vertical line, and the upper front side and end edges of the receptacle are bent to form sealing grooves 8 into which the lower front and end edges of the cover fit when said cover is in closed position. The rounded 55 upper portion 9 of the cover is formed of perforated sheet metal to permit the es-

cape of moisture from the receptacle. The cover is held in closed position by means of the hook and eye 10.

One end of the cover 7 is provided with 60 an opening 11 to receive the socket 12 of an incandescent electric lamp 13 positioned within the cover portion of the casing. This lamp is of elongated form and extends from one end of the cover to a point adjacent to the other end, and the heat of the lamp, when the current is turned on, serves to expedite the charging of the air with 65 moisture.

In order to subject the water 14 contained 70 within the receptacle to the heat of the lamp, blotting paper or other absorbent material 15 is interposed between the rounded portion of the cover and the lamp and is suspended on two or more of the supporting 75 rods 16 so that the ends of the absorbent material will depend into the water. The rods 16 hold the absorbent material spaced from the lamp and the rounded portion of the cover to permit the air to contact with 80 both sides of the absorbent material.

Current is supplied to the lamp through the wires 17 which are adapted to be connected to a source of supply by the plug 18.

In use the receptacle is filled with water 85 and the cover is closed so that the end portions of the absorbent material will extend into the water. The absorbent material will take up the water and become entirely saturated therewith and the heat of the 90 lamp when supplied with current will heat the absorbent material and the water with which it is saturated and eject said water 95 in the form of moist steam through the apertures of the cover and into the atmosphere. The degree of humidity of the air may be controlled by turning off the current to the lamp and allowing the natural or non-forced evaporation to take place when the air with 100 in a case containing the humidor is charged with the desired degree of moisture. The absorbent material will continue to draw up the water from the receptacle and provide a continuous feed to be ejected into the air 105 in the form of moist steam or by evaporation.

From the foregoing description it will be seen that the humidor is of very simple construction and is well adapted for use in supplying the proper degree of moisture without 110 in cases containing cigars and tobacco and also for other uses in which it is desired to

charge the atmosphere with a certain degree of humidity.

What I claim as my invention is:

1. A humidor, comprising a liquid holding receptacle having a perforated portion, and a heating means within the receptacle and above the surface of the liquid for controlling the evaporation of the liquid from said receptacle.
- 10 2. A humidor, comprising a liquid holding receptacle, electrical means controlling the evaporation of the liquid from said receptacle, and means for gradually elevating and presenting the liquid to the electrical means.
- 15 3. A humidor, comprising a liquid holding receptacle, a cover therefor, an electrical heating means extending into the receptacle

for controlling the evaporation of the liquid from said receptacle, and an absorbent material extending in close proximity to the heating means and into the liquid.

20 4. A humidor, comprising a liquid holding receptacle, a perforated cover therefor, supporting rods within the cover, an electrical means extending into the receptacle for controlling the evaporation of the liquid from said receptacle, and an absorbent material supported by the rods and extending over the heating means and into the liquid.

25 In testimony whereof, I affix my signature, in presence of two witnesses.

30 WALTER E. SCHIMMEL.
